UNITED STATES PATENT OFFICE.

ROLLAND CURT RICKETTS, OF CAMP VERDE, ARIZONA TERRITORY.

LIQUID-MEASURING VESSEL.

No. 839,035.

Specification of Letters Patent.

Patented Dec. 18, 1906.

Application filed May 26, 1906. Serial No. 318,890.

To all whom it may concern:

Be it known that I, ROLLAND CURT RICKETTS, a citizen of the United States, residing at Camp Verde, in the county of Yavapai 5 and Territory of Arizona, have invented new and useful Improvements in Liquid-Measuring Vessels, of which the following is a specification.

This invention relates to liquid-measuring vessels, and has for its objects to produce a comparatively simple inexpensive device of this character which may be conveniently adjusted for gradually measuring different quantities of material, one in which the 15 parts will be securely locked in active position when adjusted to reduce the capacity of the vessel, and one wherein the lower movable portion of the vessel may be quickly released and will be automatically adjusted 20 for increasing the size or capacity of the vessel.

With these and other objects in view the invention comprises the novel features of construction and combination of parts more 25 fully hereinafter described.

In the accompanying drawings, Figure 1 is a vertical longitudinal section taken centrally through a vessel embodying the invention, the section being taken on a central line 30 through the handle. Fig. 2 is a top plan view of the vessel.

Referring to the drawings it will be seen that the vessel comprises an upper section or body portion 1 and a lower collapsible portion 2, composed of a plurality of telescopic-ally-arranged relatively movable sections 3 of gradually-decreasing diameter from the uppermost to the lowermost section, which latter has a bottom 4 and is seated upon an 40 enlarged horizontal plate or disk 5, adapted to form a closure for the lower end of the body portion 1, as and for the purpose more fully hereinafter explained, the vessel being provided with a handle 6, formed from a length of thin flat spring metal bent into shape, as shown, and having its upper end attached to the side wall of the body 1 at a point adjacent the upper end of the vessel and its lower end fixed to the closure-plate 5.

50 The handle 6, which is angularly bent at a point between its ends to form a yieldable joint 7, is provided at its upper end and at its point of juncture with the vessel with a horizontal portion 8, on which is disposed a retaining member or slide 9, adapted for closing an opening 10 formed in the handle, there

being fixedly attached to the lower end of the latter a vertically-disposed locking member or arm 11 of a length equaling substantially one-half the height of the vessel and provided at its upper free end with an outturned engaging portion or lip 12, adapted to pass freely through the opening 10 and to be engaged by the slide 9 in the manner and for the purpose presently explained. 60

In practice when the lower portion 2 of the vessel is fully extended, as shown, the vessel is adapted for holding its full capacity of material, or in the present instance a quart of liquid. Under these conditions if it be 70 desired to adapt the vessel for measuring half of this quantity, or a pint, the handle 6 is compressed, thus moving the closure-plate 5 upwardly into contact with the lower end of section 1 and moving the sections 3 one 75 into another. When the lower portion has been fully collapsed, the upper end of locking member 11 will have passed through the opening 10, whereupon the slide 9 is moved toward the vessel for closing the opening and for engagement beneath the engaging portion or lip 12, thereby maintaining the handle in collapsed condition and the plate 5 pressed tightly against the lower end of section 1 for effectually closing the same. 80

When the vessel is to be again employed for measuring its full capacity, the slide 9 is moved outwardly, thereby releasing the locking member, whereupon the handle 6 will expand, thereby automatically moving 90 the plate 5 downward, thus extending the lower collapsible portion of the vessel, as will be readily understood.

Having thus described my invention, what I claim is—

1. A measuring vessel comprising an upper portion and a lower collapsible portion, a closure-member arranged at the bottom of the last-named portion and adapted for closing the lower end of said upper portion, a compressible handle for the vessel having its terminals connected respectively with the upper portion of the vessel and with the closure member, said handle being adapted when compressed to collapse the lower portion of the vessel and move the closure into contact with the lower end of the upper portion of the vessel, and means for locking the handle in compressed condition. 105

2. A vessel of the type described comprising an upper body portion and a lower collapsible portion, a closure-plate arranged at

the lower end of the collapsible portion and adapted for closing the lower end of the body portion, a compressible spring-handle having its upper end engaged with the body and its lower end connected with the plate, a locking member connected and movable with the lower end of the handle, and a keeper provided on the latter for engagement with the member to fix the handle in compressed condition.

3. A vessel of the type described comprising an upper portion and a lower collapsible portion, a closure-plate arranged at the lower end of the latter and adapted for closing the lower end of the body, a compressible spring-handle terminally engaged with the body and plate and adapted for compression

to collapse the lower portion of the vessel and bring the closure into contact with the lower end of the body portion, said handle being provided with an opening, a locking member connected and movable with the lower end of the handle, and having its upper end provided with an engaging portion adapted to pass through said opening, and a slide arranged on the handle for closing the opening and to engage the engaging portion of the locking member.

In testimony whereof I affix my signature in presence of two witnesses.

ROLLAND CURT RICKETTS.
